This application contains subject matter related to the following co-pending U.S. applications:

Application Ser. No. 29/311,574, filed Apr. 22, 2009; and Application Ser. No. 29/311,575, filed Apr. 22, 2009.

FIG. 1 is a left perspective view of a radiator grill for a vehicle according to our design, the right perspective view being mirror symmetrical;

FIG. 2 is a left side view thereof, the right side view being mirror symmetrical;

FIG. 3 is a front view thereof; and,

FIG. 4 is a top view thereof.

The broken lines are for illustrative purposes only and form no part of the claimed design.
